Primary Examiner — Stella M Reid*Assistant Examiner* — Keli L Hill(57) CLAIM

The ornamental design for a shoe, as shown and described.

DESCRIPTION

FIG. 1 is a top front perspective view of a new design for a shoe;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The dot-dot-dot lines shown in the drawings represent stitching; the dot-dot-dash lines are included for the purpose of illustrating the unclaimed portions of the article and form no part of the claimed design.
